STAGE LIGHTING SYSTEM UNIT OR THE LIKE

Charles A. Ross, 1010 W. Chestnut,

Chanute, Kans. 66720

Filed Dec. 26, 1967, Ser. No. 9,907

Term of patent 14 years

Int. Cl. D26—03

U.S. Cl. D48—20

Fig. 1.

Fig. 2.

Fig. 3.

FIG. 1 is a top, front perspective view of a stage lighting system unit or the like showing a preferred form of my new design wherein the top surface is fluted from side to side, and the end surfaces are fluted from top to bottom;

FIG. 2 is a top, front perspective view showing the detachable front panel in traveling position, the front panel being fluted from side to side;

FIG. 3 is a view similar to FIG. 2, showing a modification of my invention wherein the front panel is plain;

FIG. 4 is a top, rear perspective view of the preferred form of the design, with the back surface fluted from side to side;

FIG. 5 is a top, rear perspective view showing a modification of the invention wherein the back is plain;

FIG. 6 is a top, front perspective view showing another modification of the invention wherein the top and side surfaces are fluted from front to back;

FIG. 7 is a top, rear perspective view corresponding to FIG. 6 wherein the back is shown as fluted from top to bottom;

FIG. 8 is a top, front perspective view wherein the top is fluted obliquely and the ends are fluted from top to bottom; and

FIG. 9 is a top, rear perspective view wherein the top, ends, and back are all pleated obliquely.

In each instance where ends, bottom or other panels are not disclosed, they are similar to the corresponding parts shown.

The dominant features of my design reside in the portions shown in full lines.

I claim:

The ornamental design for a stage lighting system unit or the like, as herein shown and described.
